[57] **CLAIM**

The ornamental design for a radio control unit, as shown and described.

DESCRIPTION

FIG. 1 is a front elevational view of a radio control unit showing our new design;

FIG. 2 is a top plan view;

FIG. 3 is a left side elevational view;

FIG. 4 is a sectional view taken along line 4—4 in FIG. 1; and

FIG. 5 is a front, top and right side perspective view. The broken line matter in FIGS. 2-5 is included for illustrative purposes only and forms no part of the claimed design.
